PIPE TONG

Chester A. Lundeen, Los Angeles, Calif., assignor
to Byron Jackson Co., Vernon, Calif., a corpora-
tion of Delaware

Application June 10, 1944, Serial No. 539,662

10 Claims. (Cl. 81—66)

This invention relates generally to pipe tongs, and particularly to tongs for use in making up and breaking joints in drill pipe, well casing and the like.

A principal object of this invention is to provide a tong having an exceedingly wide range of adjustment such as will permit its use on the full range of sizes of drill pipe and well casing most commonly used.

A further object is to provide a tong of the foregoing character which consists of the minimum number of jaws, and which is adjustable in size over a wide range without the use of extra jaws.

A still further object is to provide a wide range tong which engages the pipe at a plurality of points uniformly distributed about the periphery of the pipe, to thereby uniformly distribute the radial pressure on the pipe and hence to avoid crimping it.

A still further object is to provide a wide range pipe tong comprising only two rigid jaws, thus facilitating the manipulation of the tong in applying it to and removing it from the pipe.

A still further object is to provide a wide range tong consisting of a minimum number of parts, to achieve economy of manufacture and reduce maintenance costs.

Other objects and advantages will be apparent from the foregoing detailed description of one embodiment of the invention, reference being had to the accompanying drawings wherein:

Fig. 1 is a plan view of a tong embodying the invention, adjusted to fit a pipe of relatively small diameter;

Fig. 2 is a sectional view taken on line II—II of Fig. 1;

Fig. 3 is a plan view showing the tong of Fig. 1 adjusted to accommodate a relatively large diameter pipe;

Fig. 4 is a sectional view taken on line IV—IV of Fig. 3; and

Fig. 5 is a sectional view taken on line V—V of Fig. 3.

Referring to Fig. 1 of the drawings, a preferred embodiment of my improved tong comprises a pair of opposed jaws, generally designated 1 and 2, each pivotally connected at one end thereof to a lever 3 and provided with releasable latch means, generally designated 4, at their opposite ends. The inner ends of the jaws are pivotally connected to the lever by pivot pins 5 and 6, which are spaced apart longitudinally of the lever so that as the lever is swung in a clockwise direction the jaws are constricted about the pipe, and are re-

leased therefrom by swinging the lever in the opposite direction.

In order to vary the size of the pipe-receiving recess between the jaws over a wide range, each 5 jaw comprises two relatively adjustable sections adapted to be rigidly secured together in any one of a plurality of adjusted positions. Thus, the jaw 1 comprises an inner section 7 pivotally connected to the lever 3 by the pivot pin 6, and an outer section 8 adjustably mounted on the inner section. An inner, pipe-engaging face 9 is formed on the jaw section 7, and a similar pipe-engaging face 10 is provided on the jaw section 8. It will be observed that these faces are disposed at an angle to each other to provide a substantially V-shaped recess, cooperating with a similar V-shaped recess in the opposed jaw 2 to define the pipe recess.

The pipe-engaging faces 9 and 10 are preferably disposed at an angle of approximately 90° to each other, although it will be understood that this angle may be varied considerably. However, it will be apparent that with two opposed V-shaped jaws, each having a pair of pipe-engaging 20 faces disposed at an angle of approximately 90° to each other, the four pipe-contacting points are substantially evenly distributed at approximately 90° intervals about the periphery of the pipe. Furthermore, this uniform distribution of contact points may be maintained throughout the full range of adjustment of the jaws by adjusting each of the outer jaw sections relative to the inner jaw sections into different parallel positions to maintain the 90° angular relation of the 25 pipe-engaging faces.

The adjustment of the jaw section 8 relative to the jaw section 7 may be accomplished in various ways. A simple and compact construction is, however, provided by arranging the jaw sections 30 in telescoping relation, so that the overall size of the tong is reduced as the size of the pipe recess is reduced. To this end, one of the jaw sections, preferably the inner section 7, is provided with an elongated recess defined by the upper and lower bosses 11 and 12 (Fig. 2). The outer jaw section 8 includes a male boss or projection 13 which is received within the recess between the bosses 11 and 12, and which is adapted to be rigidly secured to the bosses 11 and 12 in any one of several rectilinearly spaced positions. As shown most clearly in Fig. 2, the male projection 13 is provided with a longitudinal series of equally spaced bores 14, 15, 16, 17, 18 and 19, and the female projections 11 and 12 are provided with two sets of aligned bores 20, 20a and 21, 21a.

adapted to be disposed in registering alignment with a pair of the bores in the male projection 13. In the embodiment illustrated, the bores in the female bosses are spaced apart a distance equal to twice the distance between the bores in the male projection, but it will be apparent that they may be suitably spaced so as to align with any pair of bores in the male projection.

The jaws 1 and 8 are rigidly secured together in any one of several (herein four) different positions by inserting a pair of pins 24 and 25 in the registering bores. In Fig. 1, the pins engage the bores 14 and 16 in the male projection to secure the jaw sections in fully collapsed relation, while in Fig. 3 the pins engage the bores 17 and 19 to secure the sections in their maximum extended relation. It is obvious that two intermediate adjustments are afforded by aligning the bores 20 and 21 in the jaw section 11 either with bores 15 and 17 or with bores 16 and 18 in the male projection 13.

The jaw 2 comprises an inner jaw section 27 pivotally connected to the lever 3 by the pivot pin 5, and an outer jaw section 28 which is adjustably mounted on the inner jaw section 27 in the same manner as previously described with reference to the jaw sections 7 and 8. Inasmuch as the manner in which the jaw sections 27 and 28 are adapted to be rigidly secured together in any one of several different adjusted positions is substantially identical with that employed in the jaw 1, it is not deemed necessary to repeat the detailed description thereof. It will suffice to state that the number of bores in the jaw sections 27 and 28, and the relative spacing thereof, are preferably the same as in the corresponding jaw sections 7 and 8.

The latch means 4 is preferably of well-known construction, and comprises a latch member 30 pivotally mounted on the outer section 8 of the jaw 1, and having a latching surface 31 adapted to selectively engage a cooperating latching surface on any one of three latch lugs 32, 33 and 34. The latch is self-closing, being urged toward latching position by a spring 35. The provision of a multiple-step latch of this character, in conjunction with the spreading and constricting movements of the inner ends of the jaws by swinging of the lever 3, enables the tong to be fitted to all intermediate pipe sizes lying between the limits of each adjustment of the extensible jaw sections.

In a two-jaw tong with opposed V-shaped pipe-receiving recesses in the inner faces of the jaws, it is essential that the jaws be maintained in proper relative positions in order to obtain 4-point contact with the pipe. Because of the spaced pivotal connections between the jaws and the lever, this proper disposition of the jaws relative to each other cannot be maintained in all angular positions of the lever if both jaws are connected to the lever on fixed pivots. In order to overcome this objection, I have provided a self-adjusting movable pivotal connection between one jaw and the lever. Referring to Figs. 1, 3 and 5 of the drawings, it will be observed that whereas the pivot pin 5 extends through aligned bores in the jaw 2 and the lever 3, the pivot pin 6 is journaled in a block 36 which is mounted for limited sliding movement longitudinally of the lever in a slot 37 in the lever. The length of the slot exceeds that of the block by an amount sufficient to compensate for any tendency of the jaws to shift laterally relative to each other as the lever is swung from one extreme

position to the other. By this arrangement, the jaws are permitted to adjust themselves to the contour of the pipe and to contact it at all four points.

5 From the foregoing description of one embodiment of the invention, it will be apparent that I have provided a pipe tong having an exceedingly wide range of adjustment without the addition or substitution of other jaws. By the provision of extensible jaw sections, the angular relationship between the pipe-engaging faces of each jaw is maintained the same in all positions of adjustment, and hence the distribution of the contact points around the periphery of the pipe is maintained uniform for all pipe sizes. Furthermore, the construction is relatively simple for such a wide range of adjustment, and the tong is, therefore, easy to manipulate as well as being economical to make and to maintain in working order.

Although I have described in detail one specific embodiment of the invention, it will be understood that various modifications may be made in the construction and arrangement of parts, 25 without departing from the spirit of the invention or the scope of the appended claims.

I claim:

1. In a pipe tong, a lever, a pair of jaw members pivotally connected to the lever at spaced 30 points thereon, each jaw member comprising an inner section pivotally connected to the lever and an outer section adjustably connected to the inner section, the respective sections of each jaw member having angularly disposed pipe-engaging 35 surfaces cooperating to define a substantially V-shaped recess, and the recesses being opposed to each other to define a pipe-receiving opening, means for rigidly securing the outer section of each jaw member to its respective inner section 40 in any one of a plurality of positions to vary the size of the V-shaped recess, and latch means for releasably securing the outer sections of the jaw members together about a pipe.

2. A pipe tong as set forth in claim 1, wherein 45 said latch means includes a latch member connected to one of said outer sections and a plurality of spaced latching surfaces on the other outer section and adapted to be selectively engaged by said latch member to releasably connect said outer sections together in different spaced relation.

3. In a pipe tong, a lever, a pair of opposed jaw members pivotally connected at one end to said lever at spaced points thereon, latch means for releasably securing the free ends of said jaw members together, each jaw member comprising a first section connected to the lever and a second section associated with said latch means, a pipe-engaging surface on one section and a pipe-engaging surface on the other section angularly disposed with respect to the first-named surface to form a substantially V-shaped recess facing the other jaw member, said sections being bodily adjustable relative to each other in a direction 60 transverse to the median plane of the V-shaped recess, and means for rigidly securing the sections together in any one of a plurality of adjusted positions.

4. A pipe tong as set forth in claim 3, and including means for slidably and pivotally connecting one of said jaw members to said lever.

5. A pipe tong as set forth in claim 3, and including an element mounted on said lever for movement toward and away from the point of pivotal connection of one of said jaw members with

said lever, and means pivotally connecting the other jaw member to said element.

6. In a pipe tong, a lever, a pair of opposed jaw members pivotally connected at one end to the lever at spaced points thereon, each jaw member having a pair of angularly disposed pipe-contacting surfaces defining a substantially V-shaped recess, said recesses facing each other and cooperating to define a pipe-receiving opening, each jaw member comprising a pair of separable sections each including one of said pair of angularly disposed pipe-contacting surfaces, said sections being adjustable relative to each other in a direction transverse to the median plane of the V-shaped recess to vary the size of the recess, means for rigidly securing the sections together in any one of a plurality of adjusted positions, and means for releasably latching the free ends of the jaw members together about a pipe.

7. A pipe tong comprising a lever, a pair of opposed jaw members pivotally connected to the lever at spaced points thereon, each jaw member having a pair of angularly disposed pipe-contacting surfaces defining a substantially V-shaped recess, said recesses facing each other and cooperating to define a pipe-receiving opening, each jaw member comprising a pair of separable sections each including one of said pair of angularly disposed pipe-contacting surfaces, one of said sections including a pair of spaced projections and the other including a male projection disposed in telescopic relation to the spaced projections, means for rigidly securing said projections together in different relative positions, and means for releasably latching the free ends of said jaw members together about a pipe.

8. A pipe tong as set forth in claim 7, wherein said means for securing said projections together comprises pin members adapted to be inserted in aligned bores in said projections.

5 9. A pipe tong as set forth in claim 7, wherein said male projection includes a plurality of spaced bores and said spaced projections include a pair of spaced bores adapted to be aligned with a selected pair of bores in said male projection, said means for securing said projections together comprising pin members adapted to be inserted in the aligned bores.

10 10. A multi-size pipe tong comprising a lever, a pair of opposed jaw members cooperating to define a pipe-receiving opening, means pivotally connecting one end of each of said jaw members to said lever at spaced points thereon whereby swinging of said lever varies the size of said pipe opening in one direction, said jaw members each comprising a pair of separable sections extensible in a direction transverse to said first-named direction to vary the size of said pipe opening in said transverse direction, means for rigidly securing the sections of each of said jaw members together in different relatively extended positions, and latch means on the opposite side of said pipe opening from said lever and including means for latching the free ends of said jaw members together selectively in different positions spaced apart in a direction substantially parallel to said first-named direction, whereby said latch means supplements movement of said lever in varying the size of the pipe opening in said first-named direction.

CHESTER A. LUNDEEN.
